(57) **CLAIM**

The ornamental design for a heater and a heater with support element, as shown and described.

DESCRIPTION

FIG. 1 is a front, perspective view of a heater showing our new design;

FIG. 2 is a rear, perspective view thereof;

FIG. 3 is a left side view thereof, the right side view being a mirror image thereof; and,

FIG. 4 is a top plan view thereof.

The bottom is substantially flat and unornamented.

The dotted line showing is for environmental purposes and is not part of the claimed invention.
